CLAIM

The ornamental design for a shovel head, as shown and described.

DESCRIPTION

FIG. 1 is an isometric view of the shovel head;

FIG. 2 is a front view of the shovel head;

FIG. 3 is a back view of the shovel head;

FIG. 4 is a right side view of the shovel head;

FIG. 5 is a left side view of the shovel head;

FIG. 6 is a bottom view of the shovel head; and,

FIG. 7 is a top view of the shovel head.

The broken line showing of the shovel is included for the purpose of showing portions of the article and forms no part of the claimed design.
